UNITED STATES PATENT OFFICE.

WILLIAM H. BROWN, OF CLEVELAND, OHIO.

METHOD OF UNITING TWO PARALLEL WIRE-CABLE MEMBERS.

1,368,480.

Specification of Letters Patent. Patented Feb. 15, 1921.

Application filed December 5, 1918. Serial No. 265,379.

To all whom it may concern:

Be it known that I, WILLIAM H. BROWN, a citizen of the United States, and a resident of Cleveland, county of Cuyahoga, and State of Ohio, have invented certain new and useful Improvements in Methods of Uniting Two Parallel Wire-Cable Members, of which the following is a full and clear specification.

10 This invention has for its object to provide a simple method of permanently clamping or splicing overlapped wire cables, and it will be especially advantageous when practised in the attaching of the free end of 15 a cable to the main part thereof when said free end is bent back upon itself to form a loop or eye, since in this type of splice it has heretofore been practically impossible to expeditiously and inexpensively make a 20 satisfactory fastening for the free end of the cable.

In the drawing—

Figure 1 is a perspective view of a completed cable-eye;

25 Fig. 2 is a transverse section showing the fastening-band in position on the cable when in a die-press ready to be compressed;

Fig. 3 is a view similar to Fig. 2 showing the compression of the wrapper or band 30 completed;

Fig. 4 is a transverse section taken through the cable alongside one end of the band; and

Fig. 5 is a view similar to Fig. 3 showing 35 a modified form of die-press and also a modified form of the metal wrapper;

Fig. 6 is a side elevation of my device applied as a regular splice.

In using my method for making a cable-eye, an endless band *a* of suitable soft or ductile metal, such as copper or Norway iron, is first threaded upon the cable, then the bent-over end of the cable is passed through the band, so that the band encloses 45 both the free end of the cable and the main part. In the cable-loop or eye thus formed, a flanged thimble (not shown) is usually placed so as to be interlocked in the eye when the fastening of the overlapped 50 parts of the cable is completed.

As shown in Fig. 2, when the band is put in place on the overlapped cable members, it fits the two members freely, being materially greater in its major diameter than the 55 combined diameters of the cables. The

minor or transverse inner-diameter of the band is approximately the same as each cable, and the end-portions of the band are rounded or semi-cylindrical in order to approximately fit the cables. To complete the 60 fastening, the band is compressed in the direction of its major diameter, the metal in the band being caused by pressure to flow sufficiently to bring about a decrease in the major diameter without distorting the general shape of the band, as shown in Figs. 65 3 and 4. This compressing of the band causes the band to become slightly thicker by reason of the re-distribution of the metal throughout the mass of the band. This 70 compression is sufficient to tightly compress the parts of the cable against each other and to bring the curved ends of the band into intimate contact with the adjacent rounded surfaces of the cable. The cable being constructed, as usual, of a plurality of steel wire strands twisted together, the compression of the contacting cables against each other will cause an intimate compacting or crowding of the adjacent strands, while 75 maintaining them separate and substantially of initial diameter and without distorting the strands; and along the surfaces of contact between the cables and the band the metal of the band will be indented by the 80 strands to thereby permanently interlock, as shown in the enlarged view, Fig. 5. The compression of the band may be brought about by a die-press, such as shown 85 in my drawing, which may be operated by power-machinery or by a hand-tool, it being important, of course, that the exterior surface of the band shall be supported at all points during the compressing and flowing of the metal.

90 It will be understood that I may use either a seamless band, as shown in Figs. 1 to 4, or a band seamed longitudinally by brazing or welding, as shown in Fig. 5. In Fig. 5, I show one longitudinal edge *b* of a seamed 100 band extended inwardly to lie between the cable-sections so that when the wrapper or band is compressed, this strip *b* will be indented by the spirally-extending cable-strands and will thus materially assist in 105 combating all strains which tend to pull the cable-sections out of the band, the anchoring of the cable-sections in the band being thereby materially strengthened. In this 110 view, Fig. 5, I show the matrix of the die-

blocks arranged at an oblique angle to the line of pressure, so that the compressing of the band will not cause the band to stick in the die-blocks when the blocks are separated.

5 It will be understood, of course, that the intermediate strip *b* may be made separate from the wrapper-band *a* and simply laid in place prior to compressing the band instead of, as shown, making it integral with the band.

10 The nature and scope of the invention having been thus indicated and its preferred embodiment having been specifically described, what is claimed as new is:

15 1. The method herein described of uniting two parallel wire cable-members consisting in threading the two members in parallel relation through an endless metal band and then compressing the band to cause the 20 major diameter of the band to decrease sufficiently to compact or crowd the strands of the cable-members, while maintaining them separate and substantially of initial diameter, and also to indent the cable-strands 25 into the inner faces of the band.

2. The method herein described of forming a cable splice consisting in overlapping the parts of the cable to be spliced, inclosing the overlapped parts of the cable in an endless metal loop having a major diameter greater than the combined diameters of the two cable sections and a minor diameter approximately equal to the diameter of the cable-section, then by compression and flow 30 of metal decreasing the major diameter sufficiently to crowd the strands of the cable-sections and to indent the strands into the inner surface of the band.

3. The method herein described of uniting 40 parallel wire-strand cable-sections, consisting in placing a soft or ductile metal band around the same and then compressing the band to crowd the strands of the cables, while maintaining them separate and sub-45 stantially of initial diameter, and also cause

the strands to indent themselves into the metal of the band.

4. The method herein described of uniting wire-strand cables consisting of encompassing the sections of the cable in an elongated 50 endless band of soft or ductile metal and providing a partition of said ductile metal between the cable-sections, and then compressing the band to decrease its major diameter to cause the strands of the cables 55 to indent themselves in the partition and inner face of the band.

5. The method herein described of uniting wire-strand cables, consisting in placing around the parallel overlapped cable-sections an endless band of ductile metal having an integral strip lying between the cable-sections, then compressing the band to cause the strands of the cable to indent themselves into said intermediate strip and 60 also into the inner face of the band.

6. The method herein described of uniting parallel wire-strand cable-sections consisting in placing a ductile metal band around the same and in compressing the band with a 70 uniform pressure all around to crowd the strands of the cable without distorting or changing to any material extent the initial diameters of the cable-sections, the pressure being sufficient to cause the strands to indent themselves into the metal of the band.

7. The method herein described of uniting two parallel wire-strand cable-sections consisting in placing a ductile metal band around the same and then by compression 80 and flow of metal decreasing the diameter of the band sufficiently to crowd the strands of the cable-sections and to indent the strands into the inner surface of the band, the compression being exerted uniformly 85 at all points by a closed die.

In testimony whereof I hereunto affix my signature.

WILLIAM H. BROWN.
